[57] CLAIM

The ornamental design for a double sectioned container with double pour spout, as shown.

DESCRIPTION

FIG. 1 is a top and front exploded perspective view of a double sectioned container with double pour spout showing my new design;

FIG. 2 is a top plan view thereof;

FIG. 3 is a rear elevational view thereof;

FIG. 4 is a side elevational view thereof, the opposite side being identical; and

FIG 5 is a bottom plan view thereof.

FIG. 1

FIG. 2

FIG. 3

FIG. 4

FIG. 5
